UNITED STATES PATENT OFFICE.

EDWARD MINGAY, OF BOSTON, MASSACHUSETTS.

DESIGN FOR A HEATING-STOVE.

Specification forming part of Design No. 5,930, dated June 11, 1872.

Specification describing a Design for Air-Tight Heating-Stoves, invented by EDWARD MINGAY, of Boston, Suffolk county, Massachusetts.

The nature of my design is fully represented in the accompanying photographic illustration, to which reference is made.

A represents an oblong rectangular cast-iron base or box with round corners, and having a door, B, at one end for insertion of fuel, and a door or double doors, C C, in front, the doorway last named being provided with an ornamental guard or fender, D, in order that the doors C C may be opened and the fire exposed to view without escape of the latter into the apartment. Surmounting the base A

is an elliptical sheet-iron cylinder, having flat raised beads encircling it, and surmounted with an ornamental cast-iron top and urn.

The novelty in this design consists in the union of an oblong round-cornered base with a sheet-iron top, the base having a doorway in front to expose the fire, and an ornamental figured fender, the whole being as shown in the accompanying illustration.

I claim—

The design herein shown and explained.
EDWARD MINGAY.
